UNITED STATES PATENT OFFICE.

JOHN ALBERT PRIGGE, JR., OF NEW YORK, N. Y., ASSIGNEE TO THE WALTER M. LOWNEY COMPANY, OF BOSTON, MASSACHUSETTS, A CORPORATION OF MASSACHUSETTS.

DISPLAY-EASEL.

1,120,239.

Specification of Letters Patent.

Patented Dec. 8, 1914.

Application filed October 26, 1911. Serial No. 656,823.

To all whom it may concern:

Be it known that I, JOHN ALBERT PRIGGE, Jr., of New York, in the county of New York and State of New York, a citizen of the United States, have invented a new and useful Improvement in Display-Easels, of which the following is a specification.

My invention relates to an easel comprising three members preferably integral and 10 forming a rest or display support for a box or other article which is to be displayed in substantially horizontal position.

My invention will be understood by reference to the drawings in which it is shown 15 in its preferred form.

Figure 1 is a side elevation showing an easel embodying my invention in use. Fig. 2 is a plan of such an easel, Fig. 3 being a section on line 3—3 of Fig. 2. Fig. 4 shows 20 the blank adapted to be folded to form the easel shown in the other views.

The blank as shown comprises a single piece of cardboard or sheet metal of irregular shape and preferably scored to facilitate 25 bending. It has a long edge *a* which is preferably straight and which forms the base of the easel with edges *b*, *c* at each end at right angles to the base. When the blank is bent into easel shape the height of these 30 edges *b*, *c* from the base line *a* determines the height of the rear of the easel.

The front of the easel comprises a rectangular section *d* bounded in the blank by the score lines 1, 2 and 3, and carrying at its 35 top a tab *e*. The score lines 1 and 3 set off the wings *b*¹ and *c*¹, the outer boundaries of which are the edges *b* and *c* above referred to. The upper edge *f*, *g* of each wing slopes downwardly toward the front *d* to a point 40 below the level of the top line 2 of the front *d* and then upwardly as at *f*¹, *g*¹, to the upper corner of the front *d*. The slant of the edges *f*, *g* determines the angle of the floor on which the box is to rest and the edges *f*¹, *g*¹ furnish an abutment at nearly 45 or substantially right angles to the lines *f*, *g* to engage the end of the box and prevent it from sliding off the easel.

In making up the easel the wings are bent 50 backward along the score lines 1 and 3, respectively, thus forming a floor of proper angle to display the box and the tab *e* is bent backward and downward along the line 2 preferably so that it will rest against

the edges *f*, *g* which form a stop or retainer for the box to prevent it from sliding off. If it is desired to give the floor a different angle this may of course be done by making the lower edges of the wings *b*¹, *c*¹ at slight angles to the lower edge of 55 the front *d*. In addition means are provided for holding the wings together when the easel is set up. While other means may be used I have provided each wing with a locking tab. The wing *b*¹ is provided with 60 a tab *b*² which is scored as at 4 along the line of the edge *f*. This tab is provided with a hooked projection *b*³ laid off from the tab by the score line 5. In the same way, the wing *c*¹ is provided with a tab *c*² scored 70 as at 6 and having a hooked projection *c*³. These tabs are similarly located on the two wings and as shown the points of the hooks face the same way so that when the wings are bent back (see Fig. 2) they may be interlocked, the score line 5 on one of these tabs *b*² enabling its hook *b*³ to be easily bent to engage the other hook *c*³ and so lock the wings in place.

The setting up and utility of this easel 80 will be understood from the drawings and the variations which may be made in its construction will be apparent to those skilled in the art. As shown it is made from a single blank but this is not essential in order 85 to form a blank of the character described.

In practice the front portion *d* is useful not only as a support but also as a place for displaying an advertisement of the goods to be displayed. The proportions shown are 90 those well adapted for supporting a box or package of the kind in which candies are usually packed, but other proportions may be given to the various parts enabling the easel to display other kinds of packages. 95

What I claim as my invention is:

A knockdown display easel of closed form in plan and comprising an upright front member and two upright side members hinged one at each end of said front member and converging toward the rear of the easel, each side member being of equal height with the front member where it joins it and having an upper edge sloping downward from said front member at an angle 100 thereto to form an abutment and then upward toward its rearward end, said side members being higher at their rearward

ends than where they join the front member, said front member having a tab projecting upwardly and adapted to be bent downward and backward against said abutments, and said side members being provided with interlocking tabs adapted to be folded toward each other to hold the side

members in fixed position and also adapted when interlocked to form a floor for the articles resting on the stand.

JOHN ALBERT PRIGGE, JR.
